Primary Examiner — Garth Rademaker*Assistant Examiner* — Katie Stofko Mroczka(74) *Attorney, Agent, or Firm* — Rachel A. Kahler; Diederiks & Whitelaw, PLC; Annette M. Frawley, Esq.(57) **CLAIM**

The ornamental design for a shaped tortilla, as shown and described.

DESCRIPTION

FIG. 1 is a perspective view of the shaped tortilla according to our design;

FIG. 2 is an end view of the shaped tortilla of FIG. 1;

FIG. 3 is a side view of the shaped tortilla of FIG. 1;

FIG. 4 is a cross-sectional view of the shaped tortilla of FIG. 1, taken along line 4-4 in FIG. 2;

FIG. 5 is a top view of the shaped tortilla of FIG. 1; and, FIG. 6 is a bottom view of the shaped tortilla of FIG. 1.

The evenly-spaced broken lines in FIGS. 1 and 3-6 illustrate portions of the shaped tortilla that form no part of the claimed design. The dash-dot-dash broken lines in FIGS. 1 and 3-6 illustrate the boundary of the claimed design which forms no part thereof.
